UNITED STATES PATENT OFFICE.

EDGAR A. BIENENSTOK, OF ST. LOUIS, MISSOURI.

STAMP-AFFIXER.

SPECIFICATION forming part of Letters Patent No. 707,198, dated August 19, 1902.

Application filed May 27, 1901. Serial No. 62,080. (No model.)

To all whom it may concern:

Be it known that I, EDGAR A. BIENENSTOK, a citizen of the United States, residing at the city of St. Louis, State of Missouri, have invented a certain new and useful Improvement in Stamp-Affixers, of which the following is a full, clear, and exact description, such as will enable others skilled in the art to which it appertains to make and use the same, reference being had to the accompanying drawings, forming part of this specification, in which—

Figure 1 is a top plan view of my improved stamp-affixer. Fig. 2 is a side elevational view of the same. Fig. 3 is a rear elevational view. Fig. 4 is a sectional view on line 4 4, Fig. 1. Fig. 5 is a sectional view on line 5 5, Fig. 1.

This invention relates to a new and useful improvement in a machine for affixing stamps to mail-matter, the object being to construct a device of the character described in a cheap and compact form, utilizing a small number of moving parts, so as to reduce the liability of the machine to get out of order.

With these objects in view the invention consists in the arrangement, construction, and combination of the several parts, all as will hereinafter be described and afterward pointed out in the claims.

In the drawings, A indicates the base of the machine, from which rises a standard a. This standard is provided with a vertical opening for the reception of the shank of a plunger B.

b indicates a head on the upper end of the plunger, under which is arranged a spring b', said spring bearing at its lower end against the top of the standard a and tending to hold the plunger in an elevated position at all times.

b² indicates the head on the lower end of the plunger, through which head projects a spring-pressed pilot-plunger C. This pilot-plunger is provided with a head on its lower end, which is designed to be received in a recess in the under face of the plunger-head b², whereby when the plunger B is depressed the pilot-plunger first engages the stamp to be affixed and holds it in position while the plunger continues to descend. The plunger B is preferably of such size as to entirely cover the stamp, so that the stamp receives a uniform pressure over its entire area. The pilot-plunger C is

designed to hold the stamp in position while the plunger B severs the stamp from the strip, as will hereinafter be described.

a' indicates a table or bed upon which the envelop is placed preparatory to receiving a stamp. One edge (the back) of this table is provided with an overhanging flange a² to guide the envelop in its movement under the plunger, said envelop being arrested in a proper position under the plunger by contacting with the standard a.

In introducing the envelop under the plunger the same is preferably moved in from the side, and in this action the envelop passes under a moistening device in the form of a felt or other wiper d, which is carried upon the end of a vertical swinging frame D. The table a' is formed with an opening a³, through which the wiper d operates, the opening a³ leading to a chamber or receptacle a⁴ in the base of the machine, in which receptacle is placed water or other suitable liquid. As shown in Fig. 4, the frame D and its carried wiper are held in a lowered position by a spring d', the wiper being in contact with the liquid in the receptacle a⁴. When an envelop is introduced from the side, it raises the swinging frame D, and as it passes under the wiper is moistened before it reaches a position under the plunger B. When the plunger B is depressed, the stamp is forced down onto the moistened part of the envelop. Frame D is pivoted in an overhanging extension a⁵, secured to the standard a, which extension is provided with a guiding-ledge a⁶, resting upon the flange a². This overhanging frame also carries a bar a⁷, arranged in the path of movement of the wiper d and against which the wiper is forced when raised by the introduction of an envelop thereunder. This bar a⁷ forces the wiper into close contact with the envelop to be moistened.

In order to introduce water into the receptacle a⁴, I provide an opening a⁸ on the base, which opening is exposed, as shown in Fig. 1.

a⁹ indicates a rearward extension projecting from the base A and provided with grooves forming a guideway for a reciprocating pawl-carrying plate E. On the inner end of this plate are arranged a series of stamp-advancing pawls F, loosely mounted on a common

pintle and preferably held collectively in a groove in the upper face of the rearward extension a^9 . A spring f co-operates with these pawls to hold them in their lowered position.

5 e indicates a tongue of metal struck up from the plate E , which tongue is received in the bifurcation of an operating bell-crank lever G . This lever G is mounted upon an extension upon the standard a , its upper end 10 being slotted, as at g , to receive a pin b^3 on the plunger B . In operation as the plunger is depressed the pawl-carrying plate is moved rearwardly by the lever G , so that the teeth on its pawls, or, at least, some of them, will 15 fall into the perforations between the stamps or behind a single stamp, as the case may be, for the purpose of advancing another stamp, when the plunger rises, into position under the plunger. When at home, the teeth on 20 the inner ends of the group of pawls rest at the edge of what might be termed a "continuation" of the flange a^2 .

In order to prevent a return movement of the stamps after said stamps have been advanced by the group of pawls, I provide a wedging-pawl H , mounted in a suitable support extending up from the base, which wedging-pawl permits the stamps to be advanced by the group of pawls F , but by a 25 wedging action holds the stamps against a return movement when the grouped advancing pawls are retracted.

In order to firmly hold the strip of stamps in position to insure the severance of the 35 stamp under the plunger, I mount a presser-frame I upon the plunger-head b^2 , which presser-frame when the plunger is elevated occupies a plane slightly below the lower face of the plunger. This presser-frame is held 40 in its lowered position by means of a spring i , surrounding a shank thereof and arranged between guiding lugs or ears b^4 , secured to the plunger-head b^2 .

In operation the stamps to be affixed to letters are introduced under the plate E in the 45 form of strips, and an idle vibration is imparted to the plunger B , so as to place the first stamp in position under said plunger. The envelop to be stamped is forced under 50 the wiper until arrested in the proper position under the plunger and under the stamp in the path of the plunger. The plunger is now depressed and in so doing first retracts the frame E and its carried group of advancing pawls. The wedge-pawl H prevents the 55 group of pawls from dragging the stamp under the plunger out of proper position. As the plunger descends the pilot-plunger engages the stamp and forces it onto the envelop. Then the presser-frame I engages the 60 adjacent stamp for the purpose of holding it and its connected strip against movement, and, finally, the plunger forces the stamp in its path onto the envelop, and in so doing the 65 plunger severs said stamp from the strip. This severance may be accomplished readily in the event that a line of perforations is over

the edge of the shoulder a^{10} , which corresponds to an extension of the flange a^2 . In any event the rear edge of the plunger travels past the edge a^{10} and acts with said edge to shear the stamp from its companions and force the same onto the moistened space on the envelop.

I am aware that minor changes in the arrangement, construction, and combination of the several parts of my device can be made and substituted for those herein shown and described without in the least departing from the nature and principle of my invention.

Having thus described my invention, what I claim, and desire to secure by Letters Patent, is—

1. In a stamp-affixer, the combination with a support for the article to be stamped, of an overhanging frame, a pivoted wiper mounted in said frame, and depending toward the supporting-surface for the article to be stamped, whereby said article can pass between said frame and said wiper, and a bar with which 85 said wiper co-operates to force said wiper upon the article to be wiped; substantially as described.

2. In a stamp-affixer, the combination with a support for the article to be stamped, a 95 flange arranged upon the side of said support, an overhanging frame, a guiding-ledge on said frame and above said flange, a pivoted wiper mounted in said overhanging frame and depending toward the supporting- 100 surface for the article to be stamped, whereby said article can pass between said surface and said wiper, and a bar a^7 for co-operating with the wiper to force said wiper upon the article to be wiped; substantially as 105 described.

3. In a stamp-affixer, the combination with a support for the article to be stamped, of a plunger for affixing the stamp, a recovering-spring for said plunger, and a pilot-plunger 110 projecting beneath the main plunger immediately above the stamp to be affixed when said stamp is in position to be affixed; substantially as described.

4. In a stamp-affixer, the combination with 115 a support for the article to be stamped, of a stamp-affixing plunger, means exerting pressure against said plunger to hold it constantly in an elevated position, a pilot-plunger telescopically mounted in the lower end of said 120 first-mentioned plunger and arranged within the area of the lower face of said stamp-affixing plunger, and means co-operating with said pilot-plunger tending to hold the same constantly in a lowered position; substantially as 125 described.

5. In a stamp-affixer, the combination with a support for the article to be stamped, of a plunger provided with a head on its lower end designed to cover the stamp to be affixed, a 130 spring for holding said plunger in an elevated position above the support, a pilot-plunger projecting through said head, which head is recessed on its under side to receive the pilot-

plunger, and a spring for holding said pilot-plunger in a lowered position; substantially as described.

6. In a stamp-affixer, the combination with 5 a support for the article to be stamped, of a way for receiving a strip of stamps, said way being located on a plane above the support for the article to be stamped so as to form a shoulder a^{10} , a vibrating plate mounted to 10 travel in said way, a group of pawls mounted on said vibrating plate, a main plunger for shearing or severing the stamp at the shoulder a^{10} , a pilot-plunger for holding the stamp upon the article to be stamped while the main plunger is operating on the stamps, and a connection 15 between said main plunger and the vibrating plate; substantially as described.

7. In a stamp-affixer, the combination with a main plunger, of a presser-frame yieldingly 20 mounted thereon and normally located on a lower plane than the face of the main plunger, and a pilot-plunger; substantially as described.

8. In a stamp-affixer, the combination with 25 a main plunger, of a way for a strip of stamps, a shoulder a^{10} over which the stamps are advanced in the path of the main plunger, a pilot-plunger mounted in the main plunger

for holding the stamps in position while said stamps are being operated upon by the main 30 plunger, means for advancing the stamps in the paths of the main and pilot plunger, and a yielding presser-frame mounted on the main plunger for engaging the adjacent stamp before the main plunger severs the stamp to 35 be affixed, substantially as described.

9. In a stamp-affixer, the combination with a support for the article to be stamped, of a moistening device, a way for receiving a strip 40 of stamps, said way terminating at a shoulder a^{10} , means for advancing the stamps over said shoulder, a plunger operating in juxtaposition to the shoulder, a pilot-plunger for engaging the stamp to be affixed and forcing it onto the article to be stamped, and a presser-frame for 45 engaging the adjacent stamp and holding it while the plunger severs the stamp to be affixed from its companions; substantially as described.

In testimony whereof I hereunto affix my 50 signature, in the presence of two witnesses, this 23d day of May, 1901.

EDGAR A. BIENENSTOK.
